ELECTRON GUN POSITIONING MEANS

Rudolph O'Larte, Rego Park, N. Y., and Kurt Speck, Palisade Park, N. J., assignors to Jacques Kreisler Manufacturing Corporation, North Bergen, N. J., a corporation of New Jersey

Application August 20, 1943, Serial No. 499,356

3 Claims. (Cl. 250—162)

1

This invention relates to electron discharge devices such as, for example, cathode ray tubes.

One object of the present invention is to provide an electron-electrode formed of parts which can be easily manufactured and assembled and which are so constructed and arranged with respect to each other as to assure the correct position of the electron aperture in the tubular member and also to assure the correct positions of the apertures of the same electrode as well as of the different electrodes of the electron gun with respect to the other.

Another object of the invention is to provide an electron-electrode which can be made of sheet metal by simple cutting and bending operations and having parts which are so constructed with respect to each other that they can be assembled and secured in assembled relation without requiring welding of said parts to each other.

Another object of the invention is the provision of a cathode having the parts thereof constructed and arranged so as to facilitate the correct positioning of the electron emission element in relation to the aperture of the electrode.

Another object of the invention is to provide improved means for resiliently supporting the forward part of the gun assembly in the envelope or tube.

A further object of the invention is the provision of an electron gun assembly unit of improved construction.

The above and other objects, features and advantages of the invention will be fully understood from the following description, reference being had to the accompanying illustrated drawings. In the drawings—

Figure 1 is a side view of a cathode ray tube embodying the present invention, part of the tube or envelope being broken away for the purpose of illustration;

Figure 2 is a view, on a larger scale, partly in elevation and partly in section of the electron gun of the present invention;

Figure 2A is a sectional view on the line 2A—2A of Figure 2;

Figure 3 is a perspective view, on a larger scale, of a part of the tubular member of the first anode;

Figure 4 is a view in elevation, on an enlarged scale, of one of the apertured members of an electron-electrode of the present invention;

Figure 5 is a sectional view on the line 5—5 of Figure 4;

Figure 6 is a side view of the cathode;

Figure 7 is an end view of the cathode;

2

Figure 8 is a sectional view on the line 8—8 of Figure 2;

Figure 9 is a front view in elevation of the means for resiliently supporting the forward part of the electron gun on the envelope;

Figure 10 is a sectional view of the line 10—10 of Figure 9; and

Figure 11 is a sectional view on the line 11—11 of Figure 2.

Referring now to the drawings in detail, the cathode ray tube 10 comprises the usual glass envelope 12 and an electron gun 14 embodied in the present invention, said gun being shown by itself on a larger scale in Figure 2. As here shown, said gun comprises the grid 16, the pre-grid accelerator 18, the first anode 20, the second anode 22 and the vertical and horizontal deflecting plates 24 and 26 respectively.

One of the features of the present invention resides in the construction of the electron-electrodes 16, 18, 20 and 22, and more particularly the construction of these electrodes in respect to the tubular members and the electron aperture parts and the assembly of said parts with the tubular members and with respect to each other. This feature of the invention will now be described first with reference to the first anode 20. The tubular member of said anode comprises two semi-cylindrical members 28 and 30 formed of sheet metal and connected to each other in tube defining relation. Each of said members is substantially of the construction illustrated in Figure 3 and as there shown is provided with the internal peripherally extending grooves 32, 34 and 36 in which are engaged the peripheral ribs 38 of the apertured members 40, 42 and 44 respectively. Said apertured members are formed of sheet metal and are of the construction illustrated in Figures 4 and 5; and 40 are substantially all alike except for the size of the electron aperture 46. Said electron aperture is formed in the circular disc part 48 which is provided with an axially extending integral flange 50 which is provided with an outwardly pressed rib which constitutes said peripheral part 38. The disc part 48 is provided with a pressed rib 51 for reinforcing said part. Each semi-cylindrical part of the tubular member is provided with longitudinally extending outwardly directed flanges 52, the flanges of the companion tubular parts 28 and 30 being in close abutting relation for the full lengths of the tubular members and being held in said relation by bending portions 54 of the flanges 52 of one of the tubular parts, here shown as the tubular part 28, over

the flanges 52 of the companion tubular part, here shown as the tubular member 30. Flanges 52 of parts 28 and 30 are provided with lateral extensions 56 each having a semi-cylindrical groove 58 formed therein as illustrated in Figure 3. The lateral extensions 56 provide means for securing the tubular member constituted by said parts 28 and 30 to the insulation rods 60 and 62, the latter being positioned in the cylindrical grooves formed by the companion semi-cylindrical grooves 58 of the confronting extensions 56 of the companion parts 28 and 30.

The other electron-electrodes 16, 18, and 22 are similarly formed of companion semi-cylindrical parts like the parts 28 and 30 of the first anode 20 and are provided with apertured members like those mounted in said first anode. Thus, as illustrated in Figure 2, the grid 16 is provided with an apertured member 64, pre-grid accelerator 18 is provided with an apertured member 66, and the second anode 22 is provided with the apertured members 68 and 70, all of the same construction as that illustrated in Figures 4 and 5 with the exception of the size of the central electron aperture 46. Further, it will be understood that each of said electrodes 16, 18 and 22 are provided with grooved lateral extensions like the grooved lateral extensions 58 of the first anode 20 for securing said electrodes to the mounting insulation rods 60 and 62. If desired, the confronting companion lateral extensions may be spot-welded to each other at opposite sides of the grooves for providing a good securement of the tubular members of the several electrodes respectively to said insulation rods.

It will be understood that by reason of the provision of the peripheral grooves which receive the ribs 38 of the companion apertured members, the latter are automatically properly positioned longitudinally of the companion tubular members during the assembly of said apertured members with the companion tube forming parts of the said tubular members, and further, it will be observed that the apertured members are secured in position solely by the securement to each other of the companion tube forming parts of the tubular members, so that it is unnecessary to weld said apertured members to the tubular members. Also it will be noted that the tube forming parts of the tubular members can be easily produced by simple operations such as cutting and bending, thereby eliminating the necessity for forming the tubes by the usual sheet metal drawing operation. The elimination of the welding and drawing operations is desirable as it obviates contamination of the electrodes. It will also be understood that by constructing the electrodes as hereinbefore described the apertures of the gun are not only accurately spaced with respect to each other, but are also in correct axial alignment, this correct spacing and axial alignment of the apertures being automatically and necessarily accomplished in the act of assembling the companion tube forming parts with the companion apertured members.

The grid electrode 16 is preferably constructed as will now be more particularly described whereby the electron emission element 72 is easily mounted within the tubular electrode member and is held in predetermined position with respect to apertured member 64. Said element 72 is constituted by a tubular member which is heated by the heating element 74 positioned therein. An insulation disc 76 is fixed to tubular member 72 near the closed front end thereof and is engaged

at its opposite sides at the peripheral marginal edge thereof by the spacing member 78 and by the member 80 respectively. As illustrated in Figure 2 spacing member 78 is provided with a central aperture 82 which is in axial alignment with the aperture of member 64 and the front end of the electron emission member 72. It will be observed that the forward end of spacing member 78 abuts the inner surface of apertured member 64 and that the insulation disc 76 which engages the electron emission member 72 in fixed relation thereto abuts against a peripherally continuous shoulder formed in said spacing member between the opposite ends thereof. The peripheral edge of insulation member 76 engages the inner peripheral surface of the rearwardly extending tubular portion 84 of the spacing member 78 whereby the electron emission member 72 is positioned centrally of the tubular member of the grid electrode 16 in correct axial alignment with the aperture of member 64. Holding member 80 may be secured in position against the adjacent marginal edge of insulation disc 76 in any suitable way as by a tight fit in tubular portion 84 of spacing member 78.

The insulation rods 60 and 62 are of tubular construction and are mounted on metal rods 86 fixed at their opposite ends to the circular mica or other insulation discs 88 and 90 respectively, the opposite ends of said rods 86 being upset or riveted to said discs respectively. Disc 88 is supported within the envelope 12 by wires secured in the fused portions of said envelope at the base of the tube and secured to said disc at peripherally spaced points. The insulation disc 90 at the forward part of the gun is formed with a central opening 92 which engages around the tubular member of the second anode 22 adjacent the front end thereof at which the apertured member 68 is positioned. Said disc 90 abuts the peripheral rib 94 formed in said tubular member for the provision of the inner peripheral groove which receives the peripheral rib of said apertured member.

In accordance with the present invention, provision is made for providing a resilient abutment or support between the forward part of the gun 14 and the inner wall of the envelope 12. For this purpose the circular metal member 96 is secured to insulation disc 90 in any suitable way as by eyelet rivets 98 which are circumferentially spaced from each other and pass through companion integral portions 99 of member 96. The member 96 is provided with a plurality of circumferentially spaced spring fingers 100 which are reflexed toward the base of the tube and resiliently engage the inner wall of the envelope 12. As shown, the spring fingers 100 are spaced outward from the peripheral edge of disc 90. The spaces between the radially extending portions of the resilient fingers 100 provide room for the connection of various wires and rods to disc 90 insulated from metal member 96. The metal rods 86 which extend through the insulation rods 60 and 62 are connected, as here shown, to two of the ears 99 by which member 96 is secured to disc 90.

The deflection plates 24 are mounted on rods 102 secured at their opposite ends to disc 90 and to an insulation disc 104. The deflection plates 26 are mounted at the ends of rods 106 which pass through disc 104 in fixed relation thereto and are secured at their rear ends to disc 90.

While we have shown and described the preferred embodiment of our invention, it will be

understood that the latter may be embodied otherwise as herein shown or described and that in the illustrated embodiment certain changes in the details of construction and in the arrangement of parts may be made without departing from the underlying idea of this invention. Further, it will be understood that certain features of the present invention may be used without others. Accordingly, we do not wish to be limited to the construction herein specifically illustrated or described except to the extent which may be required by the scope of the appended claims.

Having now described our invention, what we claim and desire to secure by Letters Patent of the United States, is:

1. In an electric discharge device comprising an envelope and an electron gun mounted therein, an insulation disc fixed to said gun and spaced from the adjacent inner peripheral surface of said envelope, a member secured to said disc in face to face relation therewith in position surrounding said gun, said member being insulated from said gun by said insulation disc, and resiliently flexible means integral with said member and positioned in the space between the envelope and said disc and resiliently engaging the inner surface of said envelope.

2. In an electric discharge device comprising an envelope and an electron gun mounted therein, an insulation disc fixed to said part of the gun, a circular member secured to one face of said disc in position surrounding said part of the gun, said member being insulated from said gun by said insulation disc, and resiliently flexible means carried by said circular member and comprising circumferentially spaced radial parts spaced from said face of said disc and extending beyond the outer edge of said disc from points inwardly of said edge, said radial parts having portions spaced from the outer edge of said disc and extending beyond the other face of said disc

in engagement with the inner surface of said envelope.

3. In an electric discharge device comprising an envelope and an electron gun mounted therein, an insulation disc having a central opening in which one end of said gun engages said disc, a circular member secured to said disc in face to face relation therewith and spaced radially outwardly from said central opening, rods for supporting said gun mounted in said envelope and having end portions passing through said disc and secured to said member, said insulation disc being spaced radially inwardly of the inner peripheral surface of said envelope, and resilient means carried by said member and resiliently engaging the inner peripheral surface of said envelope.
